UNITED STATES PATENT OFFICE.

VALORIS L. FORSYTH, OF FORT WORTH, TEXAS.

DEEP-WELL PUMP.

Application filed December 10, 1924. Serial No. 755,061.

To all whom it may concern:

Be it known that I, VALORIS L. FORSYTH, citizen of the United States of America, residing at Fort Worth, in the county of Tarrant and State of Texas, have invented certain new and useful Improvements in Deep-Well Pumps, of which the following is a specification.

This invention relates to new and useful improvements in deep well pumps.

One of the objects of the invention is the provision of a pump which will deliver a full capacity discharge of liquid from the well upon each upward stroke.

Another object is to provide a liquid operated piston balanced between bodies of liquid and acquiring its upward stroke by hydraulic pressure; while its down stroke is effected through a by-pass carrying the head pressure of the elevated and stored liquid as well as by the release of the hydraulic pressure.

Advantages of the invention reside in the elimination of sucker rods and rod troubles; also the attainment of the full power applied and the requirement of less power; and the ability to use a very long stroke pump.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a longitudinal vertical sectional view of a pump built in accordance with my invention.

Fig. 2 is an enlarged cross-sectional view taken on the line 2-2 of Fig. 1,

Fig. 3 is an enlarged cross-sectional view taken on the line 3-3 of Fig. 1,

Fig. 4 is an enlarged cross-sectional view taken on the line 4 of Fig. 1,

Fig. 5 is a fragmentary vertical sectional view of a modified form, and

Fig. 6 is an enlarged cross-sectional view taken on the line 6-6 of Fig. 5.

In the drawings the numeral 1 designates the enlarged intermediate section or cylinder of a pump casing or barrel. A cap 13 screwed onto the cylinder is reduced to receive the reduced casing section 2. A cap 8 is screwed on the upper end of the cylinder

and receives the reduced upper pump section 3.

The section 2 is screwed into a foot valve casing 12 having a foot valve 10 therein. A piston 4 reciprocates in the cylinder 1 and has a reduced extension 6 projecting into the section 2 and an extension 5 projecting into the section 3. The piston and extensions have a continuous axial bore *a*. A standing valve 11 is attached to the lower end of the extension 6 at the bore.

A stand pipe 7 has its lower end screwed into the cap 13, while its upper end is screwed into a reducing elbow 21. The pipe 7 is substantially parallel to the pump barrel. A horizontal pressure pump cylinder 23 is screwed into the elbow. This cylinder may have any practical length. A solid piston 22 operates in the cylinder by a link 25 operated by a crank arm 24 from a suitable power.

A check valve case 17 is screwed on the upper end of the casing 3, and includes a check valve 15 preventing a downward flow of liquid. The valve 17 is fitted in a head 16 which has an elbow 16' at one side. A nipple 18 is screwed into the top of the head. A by-pass pipe 9 extends from the elbow 16' down to the elbow 8' of the cap 8. The nipple 18 is connected with a horizontal discharge pipe 20 by an elbow 19. The pipe 20 is connected with a tank (not shown) which is arranged to maintain a head pressure on the liquid above the valve 15 and in the by-pass pipe 9.

To make the pump ready for operation the parts 23, 7, 1, 9, 18 and 20 must be filled with oil or liquid and this may be done in any suitable manner.

In operation the forward stroke of the piston 22 forces the stand of oil in pipe 7 into the space in the casing 1 below the piston 4. This hydraulic pressure forces the piston 4 upwardly or imparts its upward stroke. The valve 10 is opened by the suction so that the space *c* is filled with oil; while the valve 11 is closed, thus elevating the oil in the bore of the piston and displacing it into the space *b* and past the valve 15 into the pipe 20. Also as the piston moves upward the oil in the space immediately above the piston 4 in the casing 1, is displaced into the by-pass pipe 9 from which the oil is displaced into the column above the valve 15. The pipe 20 being con-

nected with a tank (not shown) so that a constant head pressure is maintained in the pipe 20 and nipple 18, the oil from the bypass is discharged against this head pressure.

The piston is thus balanced except for the head pressure exerted through the bypass pipe 9. Thus upon the reverse stroke of the piston 22, the pressure of the oil in the pipe 9 and in the cylinder is sufficient to force the piston 4 downwardly thus imparting its down stroke. The oil below the piston 4 being displaced into the pipe 7 releases the piston for its downward stroke. Upon the down stroke the valve 11 is unseated and the oil or liquid collected in the space *c* is received into the bore *a* of the piston and overflows into the space *b*.

The piston 4 is elevated by the hydraulic pressure exerted through the stand of liquid in the pipe 7 which acts as a ram. This pressure is of course relieved when the piston 22 is withdrawn so that the liquid may back up in the pipe 7 and the head pressure on the liquid in the by-pass pipe 9 will immediately act to force the piston 4 downward. The cylinder 23 may be long enough to allow of the piston 22 a stroke of several feet, the cylinder 1 being made in proportion, thus giving a copious discharge of liquid at each upward stroke.

In Figs. 5 and 6 I have shown a modification in which a hook-wall or any type of packer 33 is mounted on the casing section 2 above the foot valve 12. At the upper end of the casing 26 is a cap 27 from which the pipe 20 leads. A tubular casting 28 is fastened on the top of the head 16 instead of the nipple 18. This casting has a transverse web 29 which divides the casting, and a port 30 provides a discharge below web. An elbow 31 at the top of the casting connects with the cylinder 23. An offset 32 above the web connects with the upper end of the stand pipe 7. The casing above the packer 33 is filled with liquid which flows back from the pipe 20. This liquid is under the head pressure from the pipe 20 and the head pressure is exerted back through the port 30. The piston 22 displaces the liquid through the offset 32 to the pipe 7, otherwise the operation is the same.

Various changes in the size and shape of the different parts, as well as modification and alterations may be made within the scope of the appended claims.

What I claim, is:

1. A deep well pump comprising a casing having a plurality of members, unions joining said members together, a foot valve in the lower end of the bottom casing member, a piston adapted to operate in the central member and extending therefrom into the other two members, a bore in said piston, a check valve in the lower portion of the pis-

ton bore, a check valve at the top of the upper member, a pulsator, a pipe from the said pump to the bottom of the central member, an outlet above the upper member and a by-pass pipe from the top of the lower members to the point of juncture of the upper member and the outlet pipe.

2. In a deep well pump equipment, a cylinder having three members, unions adapted to join said members together, a bored piston adapted to move in the central member, and having extensions into the other two members, a check valve in the bottom of the bored piston, a foot valve below the piston in the lower end of the bottom cylinder member, a pipe extending into the bottom of the middle cylinder member from a single cylinder force pulsator, a by-pass pipe extending from the juncture of the upper and middle cylinder members to the top of the upper member, an outlet from the upper member, and a check valve in the top of the upper member.

3. In a deep well pump assemblage, a cylinder comprised of three members suitably joined together in alignment, a piston having a central longitudinal bore and adapted to be movably mounted in the cylinder, a liquid inlet below the piston, means for connecting said inlet to a single cylinder pulsator, a by-pass between the top of the center member of the cylinder and the outlet of the top of the cylinder, a check valve in the cylinder below the outlet, a check valve in the bottom of the piston bore, and a foot valve below the cylinder.

4. In a deep well pump, an intermediate casing, reduced upper and lower casings connected with the intermediate casing, a piston working in the intermediate casing and having extensions having a working fit in the reduced casings, said piston and extensions having a continuous axial bore, a foot valve at the bottom of the lower casing, a valve in the lower end of the bore of the piston, a valve at the top of the upper casing, a liquid discharge pipe leading from the upper casing, a fluid pressure pipe connected with the lower end of the intermediate casing, means for displacing the fluid from said pipe into the intermediate casing and conducting means extending from the liquid discharge pipe to the upper portion of the intermediate casing.

5. In a deep well pump, an intermediate casing, reduced upper and lower casings connected with the intermediate casing, a piston working in the intermediate casing and having extensions working in the reduced casings, said piston and extensions having a continuous axial bore, a foot valve at the bottom of the lower casing, a valve in the lower end of the bore of the piston, a valve at the top of the upper casing, a liquid discharge pipe leading from the upper casing,

a fluid pressure pipe connected with the lower end of the intermediate casing, means for displacing the fluid from said pipe into the intermediate casing, and a by-pass pipe leading from the upper end of the intermediate casing to the upper casing at a point above the valve thereof.

6. Means for deep well pumping comprising an intermediate cylinder and connected to reduced casings, a balanced tubular piston in said cylinder extended to communicate with said casings, a fluid pressure conductor connected with the cylinder to actuate said piston, and a by-pass extended from the cylinder to a point beyond the delivery from the piston, whereby the fluid above and be-

low the piston may move therewith to balance the same.

7. In a balanced pump, a vertical container, a balanced piston therein having a fluid conducting bore extending therethrough and a valve at the lower end of the bore, whereby the fluid below the piston is elevated therethrough, means for varying the pressure upon a body of fluid for actuating the piston in one direction, and a by-pass pipe from a point beyond the delivery from said piston extending to said container to actuate the piston in an opposite direction.

In testimony whereof I affix my signature.

VALORIS L. FORSYTH.
